UNITED STATES PATENT OFFICE.

JAMES WILLIAM MACNAMARA, OF STILLWATER, PENNSYLVANIA.

DESIGN FOR A BANNER.

SPECIFICATION forming part of Design No. 21,373, dated March 8, 1892.

Application filed January 18, 1892. Serial No. 418,502. Term of patent 14 years.

To all whom it may concern:

Be it known that I, JAMES WILLIAM MACNAMARA, a citizen of the United States, residing at Stillwater, in the county of Columbia and State of Pennsylvania, have invented a new and original Design for Banners, of which the following is a specification.

The invention relates to a new and original design for a banner.

- 10 The object of the present invention is to provide an ornamental and attractive banner; and the design consists in a banner having on its front face a representation of a woman holding a flag in one hand and standing upon a representation of the moon, and a representation of the sun and its rays, said banner having on its rear face a representation of the sun, a line of stars, and a series of stripes.
- 15 Fig. 1 is a front elevation of a banner, showing my new design. Fig. 2 is a rear elevation of the same.

Referring to the drawings, 1 designates a banner having on its front face a represen-

tation 2 of a woman, who has a flag in one hand and a crown 6 upon her head.

4 designates a representation of the sun having rays 3.

5 designates a representation of the moon, upon which the woman is standing.

The rear face of the banner has a representation 7 of the sun arranged near the top of the banner.

8 designates a curved line of stars, which are arranged between the representation 7 of the sun and a series of stripes 9, extending across the banner.

11 designates a Jewish candelabrum.

What I claim is—

The design for a banner, as herein described and shown.

In testimony that I claim the foregoing as my own I have hereto affixed my signature in the presence of two witnesses.

JAMES WILLIAM MACNAMARA.
